W. A. KRENTLER

HINGE LAST

Filed June 21, 1922

UNITED STATES PATENT OFFICE.

WALTER A. KRENTLER, OF DETROIT, MICHIGAN.

HINGE LAST.

Application filed June 21, 1922. Serial No. 568,463.

To all whom it may concern:

Be it known that I, WALTER A. KRENTLER, a citizen of the United States, and resident of Detroit, in the county of Wayne and State of Michigan, have invented an Improvement in Hinge Lasts, of which the following description, in connection with the accompanying drawings, is a specification, like letters on the drawings representing like parts.

The present invention relates to boot and shoe lasts, and the object is to improve, simplify and perfect a hinge last construction.

A two-part or hinge last, while most desirable and important in the manufacture of shoes, involves considerable expense and difficulty in the uniting or hinge members, which are usually of pivotal or link construction. Furthermore, the cutting away of the wood of the forepart and heel part of the last develops weakness which limits the life of the last. Also the hinge or link devices to unite the last members wherein a plurality of parts constitute the hinge or link uniting elements, result in quickly developing looseness and wear and hence impair the continued utility of the last.

My present invention is directed to obviate these difficulties, to eliminate the cutting away of the wood of the last as much as possible, to provide an extremely simple pivotal construction, which in fact is a combined pivot and link-like uniting element and also to afford great strength as well as simplicity in the means joining the metallic uniting members to the wood of the last.

A feature consists in the ease and facility with which the last parts may be recessed or prepared to receive the metallic hinge members and said hinge members will substantially fill the recess made. Thus I am enabled to bore into each part from the dividing line of cut, a recess which is quickly and easily formed, similar in effect to that of my prior Patent 1,094,153, dated April 21, 1914—which was prepared for the tubular hinge construction, and then this recess is filled by the present link construction and the cooperating spring or springs, thus securing the advantages of lateral support on the walls of the recess.

An additional advantage is that I am enabled to assemble my hinge parts prior

to fitting them within the last and thus can complete the uniting of the last parts and hinge simply by driving in the two retaining rivets or pins in the extreme end portions of the link members at points remote from the line of cut.

Further features, advantages, and novel combinations of parts will be hereinafter more fully pointed out and claimed.

Referring to the drawings,

Fig. 1 shows a last partly in cross-section and in extended position;

Fig. 2 is a fragmentary and partial cross-sectional view of the last shown in broken, shortened or flexed position;

Fig. 3 is a cross-sectional view on the line 3—3 of Fig. 1; and

Fig. 4 is a similar cross-sectional view illustrating a modification wherein a plurality of springs are employed, and wherein also the hinge members are assembled before fitting of the last.

Referring to the drawings, the last consists of the wooden forepart 1 and heel part 2, preferably divided upon the line of cut to form the open faces 3 and 4, the knuckle joint consisting in the concave face 5 in the forepart and the projecting knuckle 6 in the heel part, and the bottom blocking and bearing faces 7 and 8 in the forepart and heel part respectively. This is a usual type of construction employing the knuckle joint hinge, and I prefer to employ the same in combination with my present type of plurality of link or combined link and pivot construction. In the heel part I form a recess 10 and in the forepart a somewhat enlarged recess 12, to receive the hinge members, and I also bore transverse recesses for the pins or rivets 14, 15 and 16. Of these rivets the central 15 is in the center or axis of the knuckle joint, and serves to act as a pivotal hinge or pin on which the last parts themselves are flexed. This pin also serves to unite the two link members 20 and 21, which latter are plates bored to receive the pin 15 at their overlapping centers, and to receive the pins 14 and 16 respectively at their ends.

In this form, as thus far described, the last with a plurality of links, will operate readily and easily, to be moved in either straightened or shortened position, and by positioning the link retaining pivots 14 and 16 eccentrically with the central pivot 15

2
the last parts will "snap" or "spring" into either position, and stay locked therein. However, I prefer to insure a positive means which will execute this action, and for this purpose I provide the spring 25. This spring may have its end portions formed to engage the pivots 14 and 16, as shown in Figs. 1 and 2, and with its central or body portion in a curve or convolute section of sufficient extent to impart the desired resiliency and also to clear the central pivot 15 with the last in extended position, as shown in Fig. 1. This spring may be either between the two links 20 and 21, as shown in Fig. 3, or I may provide a plurality of springs 25 arranged each side of the links 20 and 21, which latter are contiguous, as shown in Fig. 4. In either instance the spring aids in holding the last parts at all times in tightly assembled position, in thus automatically compensating for any wear or looseness, either along the faces 5 or 6, or at the rivet connections 14 and 16, as well as for looseness or wear on the central pivot 15. The spring or springs 25, also further add to greatly increase the locking effect to hold the last parts firmly in either straightened or shortened position, and to require considerable power to overcome the same and to snap or spring the last parts by the center.

In order to have the hinge members assembled before fitting the same to the last, I may unite the links 20 and 21 with a short rivet 30, as shown in Fig. 4, thus saving the boring through the knuckle joint for a long pivot or pin 15. In this manner I can assemble the two link members and fit the completely assembled hinge directly in the last, supplying the spring or springs 25 and driving in one rivet, for example 16, thus retaining all the same in position, then applying the forepart 1 and driving in the remaining rivet 14, or reversing this process. This feature of assembling the metallic elements outside of the assembling of the last, enables me to speed up the construction and further saves the weakening and boring through the knuckle joint or central part, while still insuring that the last parts will turn on the rivet 30 as well as on the pivot 15.

My invention is further described and defined in the form of claims as follows:

1. A two-part last, having a heel part and a forepart formed and connected for relative movement, a plurality of link members uniting said parts, and a central pivot uniting the link members and said last parts, in combination with a spring element holding said last parts united under a tension sufficient to compensate for looseness and wear. 55

2. A hinge last of the kind described, including a knuckle joint construction, a plurality of link members joined at the center of said knuckle joint and secured to the last parts at the opposite ends of said link members remote from the line of cut of the last parts, said remote securing means being disaligned with regard to the said pivot and knuckle joint feature when the last is in lengthened or shortened position, whereby the movement of the last parts from lengthened to shortened position or vice versa will be against increasing resistance until said remote uniting points are in alignment with the said center. 65 70 75

3. A hinge last of the kind described including a knuckle joint construction, a pivot pin passing transversely through the knuckle joint construction and acting as a pivot about which the last parts are movable, a plurality of link members pivotally connected at the center of the knuckle joint on said pivot pin and secured to the last parts at the opposite ends of said link members remote from the line of cut of the last parts, said remote securing means being disaligned with regard to the said pivot and knuckle joint feature when the last is in lengthened or shortened position whereby movement of the last parts from lengthened to shortened position or vice versa will be against increasing resistance until said remote uniting means are in alignment with the said pivot 90 and a resilient spring connected to the remote securing means whereby the link members are held together under a tension sufficient to compensate for looseness and wear. 95

In testimony whereof, I have signed my name to this specification. 100

WALTER A. KRENTLER.
